DRESS TRIMMING MACHINE

Richard Carillo and Anthony Napoletano,
Brooklyn, N. Y.

Application August 4, 1942, Serial No. 453,599

6 Claims. (Cl. 164—71)

This invention relates to a garment cutting machine, particularly for trimming the bottom of skirts, dresses and the like, to a straight edge prior to the hemming operation.

The salient feature of this invention is the clamping means of firmly securing the bottom portion of the dress onto the lower dress form during the cutting and trimming operation thereof in which the clamping means, dress and dress forms and dummies rotate slowly in one complete revolution while the cutting disk revolves at a very high speed sufficiently to perform the cutting and trimming operation of the bottom portion of dress while in its clamped position.

Another important feature of this invention is the vertical pedestal shaft, which is provided with a lower dress form and upper dummy having onto its bottom thereof, a Geneva-like plate clutch member, which is set onto another collar and clutch member provided with pins to engage and drive the Geneva-like plate clutch member, all of which are positioned to the required length of dress to be cut.

Another important object of this invention is the interchangeable means of using different size dress forms or dummies onto the upper rotary shafting, slidably thereon.

Other object of this invention will appear as the description proceeds in the following specification, accompanied by the annexed drawings, in which:

Figure 1 is a front elevational view in perspective, of the cutting or trimming machine of this invention, showing the trimming or cutting operation of the dress therewith.

Figure 2 is a cross-sectional view taken on line 2—2 of Figure 1.

Figure 3 is a perspective of the lower drum member secured onto the rotary pedestal sleeve shaft with the dress form or dummy mounted thereon, the curved clamping members being shown in their inoperative and open extended position.

Figure 4 is a similar view showing the dress form or dummy removed, and the gauge marking means and clutch member adjustably secured onto the upper rotary sleeve shaft member to the required dress length to be trimmed.

Figure 5 is a partially perspective view of any suitable size dress form or dummy being shown ready for mounting onto the upper sleeve member, whereon the Geneva-like plate clutch member becomes interlocked with the clutch member shown in Figure 4.

Figure 6 is a vertical cross-sectional view taken

on line 6—6 of Figure 2, shows the upper and lower sleeve driving and clutch members disengaged, and the dress clamping members being shown in their open and inoperative positions as noted in dot-lines of Figure 2.

Referring to the drawings, the numeral 15 designates a vertical support rod member or stanchion, mounted into a suitable floor bearing 16, from which the lower sleeve driving member 15a extends upwardly onto the fixed rod or stanchion 15, and an upper sleeve driving member 15b, is also mounted thereon. A bottom dress form or drum member 17 having a lower circular vertical face portion 18 and upper exterior conical portion 19, is provided with a circular groove or channel portion 20. The lower drum portion 18 has a perforated web section 21 and collaring flange 22 which is secured at 23 to the shaft 15.

A suitable clutching member 25 is adjustable on the upper sleeve 15b by means of pull rod member 26 held normally by spring action (not shown) into engagement with holes 27 spaced apart corresponding to the guide marks 28, (see Figure 4) such as by the numerals 40, 41, 42, 43, 44, 45, 46, 47, 48, 49, 50, indicating inch and half-inch marks therebetween. The holes 27 are spaced half-inch apart, so that the dress form or dummy F may be set onto the shaft 15 to the required length of the dress to be trimmed, as shown in Figures 1, 3 and 5.

The clutch member 25 has pins 30 that engage notches 31 of the Geneva-like member 32 secured to the bottom portion of the form or dummy F having a bore 33 aligning with the hole 34 of the member 32, so the different size forms or dummies F may be mounted onto the sleeve shaft 15b and be rotatable therewith by the interlocked members 25 and 32, later to be explained in operation.

Each of the clamping members 37 are arranged onto the lower base portion 18 of the drum member 17, for example, by means of a rod 38 having one end secured at 39 to the clamp member 37, and the other end secured at 40 to a chain 41 that engages a loose sprocket 42 (or pulley-wheel), the rod 38 being slidable in the fixed bearings 43 of the lower drum portion 18. A spring 44 secured to the portion 18 and rod 38 tend to keep the clamping members 37 in their extended and inoperative position, as shown in Figures 3, 4 and 6.

The other end of the chain 41 is secured to an upper clutch member 47 on upper sleeve 15b, the clutch member 47 adapted to be engaged with the

clutch or lower driving clutch member 48 secured to the lower sleeve member 15a.

A motor M drives a belt or chain 50 that drives shaft 51 and sleeve 52 engaging a gear 53 slideable on key 54, the gear 53 meshing with pinion 55 within a box member 56, the pinion driving a shaft 57 that drives the cutting disk 58, which is shown in the cutting position in Figures 1 and 2, and in the inoperative position in Figures 3, 4 and 6, in which the box member is slideable onto the track or bars 59 arranged in floor bearing members 60, by means of the rod-bars 61 secured on each side of the box member 56, the rod-bars 61 having chains 62 riding on sprockets 63, the chains being connected to a cross-bar 64 secured at 65 to a clutch shifting member 66 (see Figures 1 and 6).

The shaft 51 drives gears 70 and 71 that rotates the lower drive member 15a and clutch member 48.

A pedal 75 connects to rods 76 and 77, which is pivotally secured to a clutch arm 78, which is anchorly pivoted to the floor bearing 79. This clutch arm has pins 80 engaging a circular groove in the upper clutch bearing 47.

In operation the operator of machine steps on the foot pedal 75, whereby the clutch arm 66 moves the upper clutch 47 into engagement with the lower clutch member 48, thereby simultaneously moving the box member 56 and cutting disk 58 by the rods 61, chains 62, cross-bar 64 and shifting arm 66 that operates upper clutch member 47, and also simultaneously moving the clamping members 37, and their inner linings 37a, preferably of felt, into their gripping positions (see Figures 1 and 2), with the bottom of the dress D clamped onto lower drum portion 18, then instantly the motor switch S' is contacted by the movable point S'', the motor M being connected by a suitable current supply, which drives the belt 50, shaft 51, gears 70 and 71, sleeve 15a, clutch members 47 and 48 and upper sleeve member 15b, dress form and dummy F, in which the bottom of the dress D is rotated in direction of arrow shown in Figures 1 and 2, the cutting disk 58 turns in the reversed direction, thereby trimming the bottom of dress at the groove portion 20, the cut off portion being indicated at 90 in Figure 6, the operator of machine cuts same with a scissors, (or by any other suitable means) and removes it therefrom for the next trimming operation.

The upper sleeve driving member 15b is rotated slowly, approximately one revolution every two seconds, while the cutting disks rotate at a very high speed sufficiently to perform the cutting and trimming operation of the bottom of the dress D in a very clean and satisfactory manner.

It is to be noted that the cutting disk 58 does not revolve around the dress form or dummy or dress, but remains in a stationary mounting, as in the box-like member 56, and moves only slightly or about the same as the clamping members 37 in towards the groove or channel portion 20. Only the dress D, clamp members 37, forms F and 17 revolve.

It is to be understood that the operating mechanism hereinbefore described and shown in the drawing, is merely illustrative of my invention, and I do not confine myself to the exactness of any of the part described and shown, and reserve the right to make any alteration that may come within the spirit of this invention and within the scope of the appended claims.

Having thus described our invention, what we

claim as new and desire to obtain by Letters Patent of the United States of America is as follows:

1. In a dress trimming machine of the character described, including a fixed rod-stanchion or rod shaft extending upwardly from a fixed floor support, upper and lower sleeve members mounted thereon, said upper sleeve member having gauge inch and half-inch markings thereon, a Geneva-like plate clutching member slideable on said upper sleeve member and adapted to be set and secured to any required position thereon, a bottom dress form-and-drum having a circular base and groove portion and upper conical portion secured to the bottom portion of said upper sleeve member, a driving clutching member secured onto the bottom end of said upper sleeve member, an upper dress form or dummy of any size adapted to be mounted onto said upper sleeve member and interlocked with said Geneva-like plate clutch member, a cutting disk arranged adjacent said circular groove portion, said dress to be cut or trimmed at its bottom unhemmed portion for its required length being gauged by said markings, means to clamp the bottom portion of said dress to said circular base portion of said bottom dress form-and-drum, means to operate said upper sleeve member onto the lower portion of said fixed upright rod-stanchion, such as another sleeve member and driving clutch member, that drives the driving clutch member secured onto the end of said upper sleeve member, thereby rotating said upper sleeve member, forms and drum all together, and further means to move said cutting disk into operation with said circular groove portion of said drum, thereby cutting and trimming the unhemmed bottom portion of said dress in one cycle of revolution by said upper sleeve member, and further means to unclamp said clamping means for the removal of said dress while said operating mechanism rotating said upper sleeve member has been made inoperative and unrotatable by any suitable means therewith.

2. In a dress trimming machine of the character described, including upper and lower dress forms suitably mounted and secured onto a rotatable sleeve member rotatable onto a stationary upright stanchion, curved plate clamping members normally held in an open position from said lower dress form, said lower or bottom dress form provided with a circular groove or channel portion, said clamping members operable by rods extending through the vertical wall portion of said lower bottom dress form, said rods having chains connected thereto, said chains connecting over sprockets mounted in the perforated portions of web or base portion of said bottom dress form, and connecting to an upper driving clutch member onto the bottom of said sleeve member, said clamping plate members adapted to be drawn into their clamping positions onto said bottom dress form with the unhemmed bottom portion of a dress clamped therebetween, simultaneously said upper and lower dress forms being rotated slowly by said sleeve member and bottom clutch member by any suitable means, whereby a cutting disk arranged in a stationary mounting adjacent to the top edges of said clamping members, revolving at a high speed trims the unhemmed bottom dress portion at the circular or channel portion wherein said cutting disk operates in a stationary position, after said forms and sleeve member have rotated one complete cycle or revolution, said cutting disk and clamping members being withdrawn to their inoperative positions by

said rods, chains and driving clutch member on bottom of said sleeve member under spring action secured to said rods and said wall portion of said bottom dress form, and by a similar chain arrangement said cutting disk being also drawn from its operation into said groove or channel portion, said driving clutch member and sleeve member becoming inoperative through means for controlling the driving means therewith.

3. In a dress trimming machine of the character described, as defined in claim 1, only the dress forms and clamping members being rotatable by said sleeve member, said cutting disk being separately arranged in a stationary bearing adjacent the top edge of one of said clamping members and in alignment with said groove or channel portion in the bottom dress form or drum, said cutting disk being moved in and out of said groove or channel portion for its trimming operation of said dress bottom portion, by the bearing thereof operated by any suitable means.

4. In a dress trimming machine of the character described, the combination of a fixed stanchion, upper and lower sleeve members mounted thereon, said upper sleeve member being engaged by a slidably clutch member provided with a pull rod that is set into spaced holes in said upper sleeve member, said holes being in alignment with spaced marks on said upper sleeve member, a bottom dress form-and-drum secured onto the bottom portion of said upper sleeve member, said dress form-and-drum having a circular bottom portion and an upper conical portion and a groove portion therebetween, a cutting disk arranged adjacent said groove portion, clamping members arranged onto said circular bottom portion of said bottom dress form-and-drum, the bottom end of said upper sleeve member provided with a driving clutch member, an upper dress-form having a central bore and a clutch plate member on the bottom portion thereof, adapted to be mounted onto said upper sleeve member and interlocked therewith, means to operate said cutting disk, clamping members, driving clutch member and upper sleeve member, thereby rotating said upper dress-form and bottom dress form-

and-drum, whereby said cutting disk moves into said circular groove and trims the bottom of any material which may be on the said forms in one cycle of said forms, after which said clamping members and cutting disk are moved outwardly to their inoperative positions.

5. In a dress trimming machine of the character described, including a fixed stanchion having a rotatable sleeve member mounted thereon, an upper dress-form and a bottom dress form-and-drum suitably arranged onto said sleeve member, said bottom dress form-and-drum provided with clamping members, a dress adapted to be fitted onto said forms and clamped by said clamping members at the bottom portion thereof, a cutting disk arranged therewith, means to rotate said sleeve member, dress forms, dress and clamping members, whereby the bottom unhemmed portion of said dress is trimmed by said cutting disk, and means to make inoperative said sleeve member, dress forms, dress and clamping members, and cutting disk, whereby the dress may be removed for the next trimming operation.

6. In a dress trimming machine of the character described, a fixed stanchion and rotatable sleeve mounted thereon, an upper dress-form and a bottom dress form-and-drum suitably arranged thereon, said bottom dress form-and-drum provided with clamping means, a dress adaptable to be arranged onto said dress forms with the bottom unhemmed portion firmly secured by said clamping means to the bottom dress form-and-drum, a cutting disk arranged in a stationary and movable bearing adjacent said clamping means and said bottom dress form-and-drum, means to rotate all of said sleeve, dress forms, clamping means and dress therewith, and to operate said cutting disk, whereby the bottom unhemmed portion of said dress is trimmed in one cycle of said forms, and means to release said clamping means and make inoperative said rotatable sleeve, dress forms, for the removal of said trimmed dress for the next trimming operation.
